J. H. BOYE

CURTAIN ROD

Filed May 19, 1926

Inventor:
James H. Boye,
By Fisher, Towle, Clapp & Soane, Atty.

UNITED STATES PATENT OFFICE.

JAMES H. BOYE, OF CHICAGO, ILLINOIS, ASSIGNOR TO JAMES H. BOYE MANUFACTURING COMPANY, OF CHICAGO, ILLINOIS, A CORPORATION OF ILLINOIS.

CURTAIN ROD.

Application filed May 19, 1926. Serial No. 110,069.

This invention relates to improvements in curtain rods, having reference more particularly to what are commonly known as flat or oval rods, which are made of a strip of sheet-metal having its upper and lower edges folded over on the rear side for stiffening purposes, and, in the case of extensible rods, made in two telescoping sections which mutually support each other.

In Letters Patent No. 1,309,060, granted to me July 8, 1919, I have disclosed a curtain rod of this type wherein the inner end of the inner telescoping member is equipped with a transversely elastic wire loop member rigidly secured in and projecting from the end of said inner member and engaging under compression within the outer telescoping member; said elastic wire loop serving to prevent sagging of the two sections of the curtain rod and maintaining their end-wise alignment, and also preventing the rods from falling apart and stiffening the rod in a horizontal plane, preventing it from bowing outwardly or inwardly relatively to the window casing, and also serving as a leader to facilitate the threading of the inner rod section through the hem of the curtain.

Extended practical experience with the rod of the aforesaid patent has proved that, while it efficiently performs the above-stated functions, it develops some faults and defects under certain circumstances, which it is the object of the present invention to overcome. For instance, if telescoped into the outer rod section to a point where it encountered the elbow of the latter it would bend and get out of place, becoming either too loose or too tight; and if it was dropped on the floor it would be bent out of shape or driven into the rod and its utility impaired or destroyed.

My present invention is in the nature of an improvement upon the stiffening feature of my aforesaid patent, and, as above stated, has for its main object to provide a stiffening member which shall be free from the faults above-noted and will not change its shape or lose its functional capacity under such accidental conditions.

My invention, in two practical forms in which the same may be embodied, is illustrated in the accompanying drawings wherein—

Fig. 1 is an elevation of the inner adjacent

ends of two telescoping rod sections, shown separated, showing my improved spring stiffener mounted in the end of the inner section, and the latter partly in vertical section;

Fig. 2 is a view of the same parts telescoped, with a portion of the outer rod section in vertical section;

Fig. 3 is a top plan view of Fig. 2, with the outer rod in horizontal section;

Fig. 4 is a view similar to Fig. 2, showing a modification wherein the spring stiffener is housed wholly within the inner rod section;

Fig. 5 is a fragmentary top plan of Fig. 4 with the outer rod in horizontal section;

Fig. 6 is a vertical cross-section on the line 6—6 of Fig. 2; and

Fig. 7 is a vertical cross-section on the line 7—7 of Fig. 4.

Referring first to the form of the invention illustrated in Figs. 1, 2, 3 and 6, 10 and 11 designate the outer and inner telescoping sections of the curtain rod or bar, the outer ends of which are, in practice, detachably supported in and by end brackets (not shown) secured to a window casing. These rod sections 10 and 11 are substantially flat metal strips having their longitudinal marginal portions folded inwardly on the rear side of the bar through approximately half the width of the latter thus forming a narrow slot between them, as clearly shown in Fig. 6.

Where telescoping sections of a curtain rod of the general form herein illustrated are drawn apart to within a few inches of the point of separation, there is a tendency of the sections to fall apart during handling of the rod in mounting the same, as well as a noticeable sag at the center when the rod is mounted, unless some provision be made to insure ample friction between the two sections and to automatically take up slack or lost motion between them. As stated, devices more or less satisfactorily fulfilling these purposes have heretofore been proposed, but my present invention is the result of an effort to provide a rod-stiffening and slack-eliminating device that will perform these functions more efficiently and with less liability to accidental injury or destruction than heretofore. To these ends I form in the upper and lower edges of the inner rod section 11 openings 12, and at the rear end of 110

each opening I bend inwardly a tongue 13 of metal to form a stop for the inner end of the stiffening member. This latter comprises a generally U-shaped loop 14 of comparatively heavy spring wire. The two limbs of the loop are securely anchored in the end of the rod section by mashing the metal of the front and rear walls thereon down around and beneath said limbs, as clearly shown at 15 in Fig. 6. The arms of the loop 14, at points registering with the openings 12 of the rod are bowed outwardly, as shown at 15, so as to normally extend through and beyond said openings when the rod sections are separated, as clearly shown in Fig. 1, and the extreme inner end portions of the arms of the loop are bent inwardly in a direction substantially transverse to the axis of the rod, as shown at 16, and abut squarely against the inwardly pressed tongues 13 of the rod.

When the rod sections are telescoped together, the rounded outer surfaces of the bends 15 of the loop are forced inwardly by contact with the upper and lower edges of the outer rod section, thus exerting a compressive and contracting action on the wire loop 14. It will thus be seen that the expansive action of the spring loop, and the opposed compressive action of the outer rod section thereon occur at a point remote from the closed end of the loop and at a point approximately coincident with the open end of the loop, so that substantially the maximum or full spring action of the loop is utilized. The portion of the loop that projects from the end of the rod is smaller and narrower than in my aforesaid Letters Patent, while the inner or foot portion is rested squarely against the abutment lugs or stops 16. These features, together with the fact that the loop is made of much heavier stock than heretofore, render it substantially proof against deformation or breakage in case it strikes the floor or is jammed too far into the outer rod section. At the same time, the projecting end or head of the loop facilitates the threading of the rod through the hem of a curtain. The outwardly bowed portions 15 of the legs of the loop projecting through the holes in the walls of the inner rod not only create ample friction in the walls of the outer rod to prevent the rods from falling apart and to take up slack at one end of the telescoping parts, but they also serve, in conjunction with the stop 16 to securely lock the loop in the rod against being either driven into or pulled out of the latter.

The form of the invention illustrated in Figs. 4, 5 and 7 embodies the same operative principle as that of Figs. 1, 2, 3 and 6, but reverses the position of the spring loop member relatively to the rod carrying the same, locating it wholly within the rod. In this

case since the loop member is wholly housed within the rod and as a consequence is not subject to accidental forces tending to drive it either inwardly or outwardly, the abutment stops, such as 16, may be dispensed with, the loop member maintaining its position within the rod simply through engagement of the protuberances 15 of its limbs with the opposite ends of the holes or slots 12. This form of the invention has all of the described advantages of the other form save only that it lacks the projecting portion of the loop to serve as a curtain leader. This lack, however, may be supplied by convexing the end of the front wall of the inner rod, as shown at 17 in Fig. 4 and giving to the upper and lower edge walls a rearwardly oblique form, as shown at 18 in Fig. 5.

While I have herein shown and described my invention as embodying a transversely elastic member having portions projecting through openings in the walls of the inner rod section and bearing under friction against the corresponding portions of the walls of the outer section, the broad principle of the invention lies in the provision of parts in or on the inner rod section adapted to expand against the inner wall of the outer rod section into frictional holding engagement with the latter, and located inwardly of the end of the inner rod section.

I claim—

1. In a telescoping curtain rod, the combination of an outer rod section, an inner rod section formed with diametrically opposed openings in its walls, and a transversely elastic member mounted in said inner rod section having protuberances projecting through said openings into frictional bearing engagement with the inner walls of the outer rod section, the portions of said protuberances nearest the telescoping end of said inner section being inclined to permit said outer section to cam the said projections inwardly when said inner section is entered into the meeting end of said outer section.

2. In a telescoping curtain rod, the combination of an outer rod section, an inner rod section formed with diametrically opposed openings in its walls, and a transversely elastic spring wire loop mounted in said inner rod section and having its limbs formed with outwardly bowed portions projecting through said openings into frictional bearing engagement with the inner walls of the outer rod section.

3. In a telescoping curtain rod, the combination of an outer oval rod section, an inner oval rod section formed with openings through its upper and lower edges, and a U-shaped spring wire loop mounted in said inner rod section and having its limbs adjacent to their free ends formed with outwardly bowed portions projecting through

said openings into frictional bearing engagement with the upper and lower edge walls of said outer rod section.

4. In a telescoping curtain rod, the combination of an outer oval rod section, an inner oval rod section formed with openings through its upper and lower edges and with inwardly extending stops in rear of said openings, and a transversely elastic member mounted in said inner rod section abutting at one end thereof against said stops and formed with protuberances projecting through said openings into frictional bearing engagement with the upper and lower edge walls of said outer rod section.

5. In a telescoping curtain rod, the com-

bination of an outer oval rod section, an inner oval rod section formed with openings through its upper and lower edges and with stops swaged inwardly from the rear ends of said openings, and a transversely elastic U-shaped loop secured in said inner rod section with its closed end projecting beyond the end thereof, the limbs of said loop being formed with outwardly bowed portions projecting through said openings into frictional bearing engagement with the upper and lower edge walls of said outer section, and the free ends of said limbs abutting against said stops.

JAMES H. BOYE.
